[57] CLAIM

The ornamental design for a storage container lid with compartment, as shown and described.

DESCRIPTION

FIG. 1 is a top right front perspective view of a storage container lid with compartment showing our new design; FIG. 2 is a top plan view thereof;

FIG. 3 is a left side elevational view thereof;

FIG. 4 is a right side elevational view thereof;

FIG. 5 is a front elevational view thereof; the rear elevational view being a mirror image; and,

FIG. 6 is a bottom plan view thereof.

The broken lines are for illustrative purposes only and form no part of the claimed design.
